UNITED STATES PATENT OFFICE

2,652,976

SEXTANT

Philip Francis Everitt, Seven Kings, and John Keeble, Ilford, England, assignors, by mesne assignments, to Kelvin & Hughes Limited, Glasgow, a British company

Application October 4, 1949, Serial No. 119,493
In Great Britain October 5, 1948

3 Claims. (Cl. 235—61)

1

This invention relates to sextants of the kind in which an integrating device gives an average of continuous readings. It has been proposed to provide such an arrangement in which concentric disc dials are provided to give the required readings at one side of the instrument while other readings are observed through windows in an adjacent side of the instrument.

The main object of the present invention is to provide a device in which the mechanism is of simpler construction than heretofore and all readings can be taken from one side of the instrument e. g. at right angles to the sighting telescope.

According to the invention an integrating device has a cone which drives a cylinder through one or more balls carried in a cage that is driven along the cylinder, and the cylinder is geared to a shaft which carries the cone rotatably thereon, and a series of five drums are mounted around the shaft and marked on their peripheral surfaces, two indicating degrees and minutes of altitude respectively and the other three being integration aligning drums, two of which are connected respectively to the shaft and the cone and are geared by differential gearing to the third, the arrangement being such that after use the three integration drums are reset to their initial positions the other drums directly indicate the average altitude.

Thus the markings on the drums can all be read from one side of the instrument, and a simple and reliable mechanism is used.

A constructional form of the invention will now be described by way of example with reference to the accompanying diagrammatic drawings wherein:

Figure 1 is a view partly in vertical section and partly in elevation of a perisopic sextant made in accordance with the invention;

Figure 2 is a vertical sectional view of the integrating mechanism shown in elevation in Figure 1;

Figure 3 is a sectional view on the line 3—3 on Figure 2 with certain parts (a counter shaft and parts carried thereby) removed;

Figure 4 is a sectional view on the line 4—4 on Figure 2;

Figure 5 is a perspective view of a detail shown in Figure 2;

Figure 6 is an axial view of the parts shown in Figure 5 drawn to a smaller scale; and

Figure 7 is a sectional view on the line 7—7 on Figure 6.

The sextant casing has a box-like part 10 and a perisopic tube 11 and an eyepiece telescope 9.

2

In the upper end of the tube 11 is mounted a sighting prism 12 adjustable by means of an arm 13 the lower end of which is fixed to a nut 14 on a micrometer screw 15 associated with an anti-back lash nut 16. Thus the means comprising the prism 12 is adjustable by the screw 15 according to observed altitude. The screw 15 is carried by a spindle 17 which carries a worm-wheel 18 driven by worm 19 which in turn is driven by an electric motor 20 through a reversible drive controlled by any suitable switch and finger control so that the operator by driving in one direction or the other when required can adjust the prism according to observed altitude by retaining the heavenly body under observation in the eyepiece telescope.

The spindle 17 also carries a pinion 21, having a back-lash adjuster 23, in mesh with a gear-wheel 22 that is fixed to a sleeve 24 that carries a cone 25 that is fixed to the sleeve 24. The cone is carried in bearings 26, 27, and supports a spindle 28 on which it is freely rotatable.

The cone drives balls 30, which drive a cylinder 32 carried on a spindle 33 which carries a gear-wheel 34 in mesh with a pinion 35, and backlash adjuster 36, on the spindle or countershaft 28.

The spindle 33 is mounted in a bracket 38 that is pivotally supported on hardened cones 39, 40 (Figure 4). A leaf spring 41 presses on the bracket to hold the cylinder against the adjacent ball 30. The balls 30 are carried by a cage 42 to which is attached a rack 44 driven by a motor and pinion (not shown) at a constant speed.

Five reference drums 1, 2, 3, 4, 5 are provided side by side and coaxial with the spindle 28. They can all be seen through one or more appropriate openings or windows in one side of the box 10. The drums 1, 2, 3, all carry markings such as A, B, C, etc., to facilitate resetting them to their initial or zero positions. The drums 4 and 5 are marked in degrees and minutes of altitude respectively.

Looking at the sighting windows the drums are 1, 2, 3, the integration aligning drums; No. 4 the degree indicating drum, and No. 5 the minute indicating drum. No. 1 is secured to the aforesaid shaft 28 and No. 3 and No. 5 are mounted on the sleeve 24 attached to the cone. Two drums 3 and 5 are provided because 3 carries alignment markings and 5 carries minute markings which is more convenient than having both sets of markings on one drum. No. 1 carries pinions 6 meshing with a sun-wheel 7 carried by the sleeve 24 and with a sun-wheel 8 carried by drum 2, the first sun-wheel having one tooth less than

the other sun-wheel so that drum 2 has differential movement. Drum 4 is carried freely and driven by a gearing device 9, mounted on an eccentric 48 on the sleeve 24, and connected to a fork 47 engaged by an eccentric 49 on the end of the spindle 17. The device 9 consists of inner and outer pinions the inner one having one tooth less than the outer pinion. The outer wheel moves one tooth for every revolution of the eccentric 48. The gearing 9, 47, 48, 49, is of known type sometimes called a "two-gear clock mechanism." The inner of the pinions 9 must be restrained from rotating. The fork 47 is fixed at one end to the inner pinion and prevents the inner pinion from rotating. Movement of the eccentric 48 causes the inner pinion to move eccentrically so that its teeth engage progressively with the teeth of the outer of the pinions 9. As there is one tooth less on the inner pinion than the outer pinion, the latter moves round one tooth for every revolution of the eccentric 48. The eccentric 49 keeps the inner pinion with the uppermost tooth always uppermost. Without the eccentric 49 the upper tooth would oscillate off dead centre corresponding to the rocking motion of the fork 47. Drums 2 and 4 are freely mounted on the sleeve 24 and drums 3, 5 are fixed on the sleeve 24.

The operation of the device is as follows:

The operator precomputes the approximate altitude of the heavenly body to be observed, and sets the computed figure on drums 4 and 5 by operating the motor 29. This will not affect the drums 1, 2 and 3 because the rack 44 will be stationary and the ball drive 38 will be at the left hand end of Figure 2 giving a 1:1 drive ratio between the cone 25 and the cylinder 32. Then he sights the heavenly body and starts the drive to the rack 44 which advances uniformly. During the movement of the rack 44 he continues to maintain the heavenly body in the telescope eyepiece sight by operation of the motor 29 whereby the cone is driven variably as controlled by the operator and whereby motion according to the sighting angle is applied through sleeve 24 to the drum 3 and is also applied through the cone, balls, cylinder, and spindle 28, to the drums 1 and 2 this motion being varied according to the position of the balls along the cone; at the same time the drum 5 is driven from the sleeve 24 and the drum 5 drives the drum 4 through the two gear clock mechanism. After any period of reading the integrator drums 1, 2 and 3 are reset to bring their zero marks into alignment by operating the motor 29 and screw 15 (without yet returning the rack 44), and the average altitude is then directly indicated by the drums 4 and 5.

It is not necessary to return the drums 4, 5, to their original positions as they can start from any position. The drums 1, 2 and 3 and rack 44 are finally brought back to their normal positions with these drums in alignment and the instrument is then ready to start a fresh operation.

The invention may be used in conjunction with the invention described in the specifications of applications of even date Nos. 119,492-4-5.

Theory of integrator

The action of the above described mechanism is as follows:

Suppose the gear ratio between the cone and the cylinder at time t is

$$(A+Kt)$$

where A is the initial gear ratio, K is a constant depending on cone angle and speed of travel of ball box. To cone, impart a small rotation dH (omitting constants and H being the initial altitude). The cylinder will turn by an amount

$$dH(A+Kt)$$

Then if $A=1$ i. e. the initial gear ratio being 1:1 the relative movement of the cone and cylinder is

$$dH(1+Kt) - dH = dHKt$$

Then, over a period of integration the total relative movement is

$$\int_0^H Kt + dH$$

Now, the required average altitude H^a

$$= \frac{1}{T} \int_0^T Hdt$$

Integration by parts:

$$\int_0^T Hdt = [H^t]_0^T - \int_0^H tdH$$

where H^t is final altitude at time T .

Then

$$\begin{aligned} \frac{1}{T} \int_0^T Hdt &= \frac{[H^t]_0^T}{T} - \frac{1}{T} \int_0^H tdH \\ &= H^t - \frac{1}{T} \int_0^H tdH \\ &= H^t - \frac{\int_0^H KtdH}{KT} \end{aligned}$$

Thus the average consists of the final altitude minus an amount

$$\frac{\int_0^H KtdH}{KT}$$

which is the relative amount turned back to bring the drums 1, 2, and 3 into alignment since the misalignment

$$= \int_0^H KtdH$$

and relative gear ratio is KT .

We claim:

1. A sextant having a cone, means for driving the cone in accordance with observed altitude, a cylinder, a ball device for driving said cylinder from said cone, means for traversing the ball device along the cone and cylinder, a shaft on which the cone is rotatably mounted for independent rotation, means for driving said shaft from said cylinder, five drums mounted for rotation about the axis of said shaft and marked on their peripheral surfaces so that two of said drums indicate minutes and degrees of altitude respectively and are driven from the cone, the other drums being integration aligning drums, the first of said integration aligning drums being attached to said shaft, the second being connected to and driven by the cone, and the third being freely mounted for receiving differential rotation from the first integration aligning drum and the cone.

2. A sextant as claimed in claim 1 having a micrometer screw parallel to the axis of the cone, a reversible motor reversible means for driving the screw from the motor, means adjustable by the screw according to observed altitude, and gear wheel connecting the screw and cone.

3. A sextant as claimed in claim 1 wherein said means for driving the cone includes an electric motor, a spindle, a worm and worm-wheel driving said spindle, a sleeve, and gearing connections between the sleeve and spindle, said sleeve carrying the cone and the minute indicating drum, and a reduction device conveying motion from the spindle to the degree indicating drum to provide the operative connection between said degree indicating drum and said means for driving the cone.

PHILIP FRANCIS EVERITT.
JOHN KEEBLE.
